UNITED STATES PATENT OFFICE.

NATHAN M. STONE, OF CHICAGO, ILLINOIS.

SUPPORT FOR MIRROR-FRAMES AND THE LIKE.

1,262,712.

Specification of Letters Patent. Patented Apr. 16, 1918.

Application filed October 7, 1916. Serial No. 124,406.

To all whom it may concern:

Be it known that I, NATHAN M. STONE, a citizen of the United States, and a resident of the city of Chicago, county of Cook, and State of Illinois, have invented certain new and useful Improvements in Supports for Mirror-Frames and the like, of which the following is a specification.

My invention relates to improvements in supports for mirror frames and the like, and has for its object the production of a device of this character which will be of durable and economical construction, one which may be readily and easily adjusted to operative condition or to collapsed condition to permit of ready storage or shipment, and a further one which will be highly efficient in use. Other objects will appear hereinafter.

20 The invention consists in the combinations and arrangements of parts hereinafter described and claimed.

The invention will be best understood by reference to the accompanying drawings forming a part of this specification, and in which:

Figure 1 is a partially sectional front elevation of one form of the device, embodying the invention,

30 Fig. 2, a central vertical section of Fig. 1, Fig. 3, a view similar to Fig. 1 showing another form of construction,

Fig. 4, a side elevation of Fig. 3,

Fig. 5, a view similar to Fig. 1 of another form of construction,

Fig. 6, a central vertical section of Fig. 5, and

40 Fig. 7, a partially sectional front elevation of still another form of the construction.

The device comprises a comparatively flat base consisting of a metallic shell which is formed of upper and lower parts 1 and 2. The peripheral portions of the sections 1 and 2 are overlapped, and within said shell

45 is a filling of cement and sand, or other suitable comparatively heavy plastic material. In the manufacture of the device, the base parts 1 and 2 are first filled with plastic ma-

terial, the same being permitted to rest until the plastic material has thoroughly dried and set. When the filling has thus dried and set the base formed is exceptionally solid and heavy which is of particular advantage in that the same adds stability to the construction, the mirror frame or other frame which may be supported above the base, being permitted to be adjusted to any position without fear of the device becoming unbalanced and toppling over.

Projecting centrally through the base is a bolt 4 with which coöperates a nut 5, the base section 2 being counter-sunk, as seen, to accommodate said nut. The upper end of bolt 4 serves as a means of fastening for a substantially U-shaped connecting member 6, said bolt passing centrally through the bight portion of member 6, as seen in the several views. Interposed between said member 6 and the upper side of the base is a ferrule or washer 7, said ferrule and the member 6 being clenched to the bolt 4 so as to rigidly connect said parts together, thus serving as a means of holding said bolt against rotation in the placing of nut 5 thereon.

Arranged above the member 6 is a substantially U-shaped supporting member 8 having a substantially rectangular projection or tongue 9 at its lower or bight portion which fits snugly between the sides of member 6. Said projection 9 and member 6 are pivotally connected by means of a pivot pin 10 which passes through said parts, as clearly shown in Figs. 1 and 2, knurled nuts 11 threaded on the ends of said pivot pin affording means for clamping the parts together in order to lock the support member 8 in positions of pivotal adjustment. A sleeve 12 arranged upon pivot pin 10 between the sides of projection 9, obviously coöperates with the nuts 11 in the clamping of the supporting member 8 to the member 6.

The member 8 serves as a support for a frame 13 of a mirror or the like, which is pivotally connected at diagrammatically opposite points to the ends of said member

8 as at 14. With the construction set forth it will be seen that the frame 13 may be readily adjusted about a horizontal pivotal axis relative to the member 8 in order to 5 position the mirror in any position desired. Also the member 8 may be pivotally adjusted to facilitate such positioning of the mirror and if desired said member 8 may be 10 swung all the way down to horizontal position in order to collapse the construction into compact form for convenient storage or shipment.

The form shown in Figs. 3 and 4 is the same as that as above described except that 15 projection 9 of the frame 8 is connected with the member 6 by means of pivot members 15 which pivotally and slidably engage with the elongated slots 16 formed in the sides of member 6. Upon the sides of projection 9 20 are also provided laterally projecting studs 17 adapted for engagement with notches 18 provided in the upper ends of the sides of member 6. The construction is such, as will be seen, that the member 8 may be pivotally 25 adjusted by simply first raising the same in order to disengage the studs 17 from the notches 18. Said studs thus serve as a means for holding the frame 8 in upright position, the construction, however, being capable of 30 being collapsed for convenient storage or shipment as above mentioned in connection with the forms shown in Figs. 1 and 2. The construction shown in Figs. 5 and 6 is the same as that heretofore described except 35 that the sides of member 6 are formed with inwardly extending depressions 20 which are adapted for engagement with corresponding depressions 21 formed in the adjacent sides of projection 9 of frame 8. 40 Said depressions 20 and 21 are adapted to yieldingly hold the supporting member 8 in upright position, permitting however of rocking of said supporting member to horizontal position, when desired, upon the application of sufficient pressure to said member 8 to dislodge the depressions 20 from the 45 depressions 21.

In the form shown in Fig. 7 the intermediate connecting member 6 is dispensed with, simplifying the construction to this 50 extent. This construction, however, is not collapsible as is the case with the other three forms although the frame 13 is capable of pivotal adjustment about the points 14.

55 While I have illustrated and described the preferred forms of construction for carrying my invention into effect, these are capable of variation and modification without departing from the spirit of the invention. I, 60 therefore do not wish to be limited to the precise details of construction set forth, but desire to avail myself of such variations and modifications as come within the scope of the appended claims.

Having described my invention what I 65 claim as new and desire to secure by Letters Patent is:

1. A frame support comprising a base; a supporting element; an adjustable pivotal connection between said supporting element 70 and said base, said connection comprising a substantially U-shaped member connected with said base; a connecting portion at the lower side of said supporting element engaging between the sides of said U-shaped member and pivotally connected therewith; and means coöperating with said sides of said U-shaped member for locking said supporting element in positions of said pivotal adjustment, substantially as described. 75

2. A frame support comprising a base; a substantially U-shaped supporting element; an adjustable pivotal connection between said supporting element and said base, said connection comprising a substantially U- 80 shaped member connected with said base; a substantially rectangular projection at the bight of said supporting element fitting between the sides of said U-shaped member; and a horizontally extending pivot pin passing through and pivotally connecting said projection and said sides of U-shaped member, substantially as described. 85

3. A frame support comprising a base; a substantially U-shaped supporting element; 90 an adjustable pivotal connection between said supporting element and said base, said connection comprising a substantially U-shaped member connected with said base; a substantially rectangular projection at the bight of said supporting element fitting between the sides of U-shaped member; a horizontally extending pivot pin passing through and pivotally connecting said projection and said sides of said U-shaped member; 95 and means for locking said supporting element in positions of pivotal adjustment, substantially as described. 100

4. A frame support comprising a base; a supporting element; an adjustable pivotal 110 connection between said supporting element and said base, said connection comprising a substantially U-shaped member arranged above said base; a connecting element passing through and connecting said base and 115 the bight portion of said U-shaped member; and a pivotal connection between said U-shaped member and the lower portion of said supporting element, substantially as described. 120

5. A frame support comprising a base; a supporting element; an adjustable pivotal connection between said supporting element and said base; said connection comprising a substantially U-shaped member arranged 125 above said base; a connecting element passing through and connecting said base and the bight portion of said U-shaped member;

a ferrule arranged on said connecting element and interposed between said U-shaped member and said base; a rigid connection between said supporting element and said 5 U-shaped member and ferrule; and a pivotal connection between said U-shaped member and the lower portion of said supporting element, substantially as described.

In testimony whereof I have signed my name to this specification in the presence of 10 two subscribing witnesses.

NATHAN M. STONE.
